UNITED STATES PATENT OFFICE.

WILLIAM M. CHRISTOPHER, OF TONAWANDA, NEW YORK.

BROOM-HEAD HOLDER.

1,076,347.

Specification of Letters Patent. Patented Oct. 21, 1913.

Application filed March 29, 1912. Serial No. 687,188.

To all whom it may concern:

Be it known that I, WILLIAM M. CHRISTOPHER, a citizen of the United States, residing at Tonawanda, county of Erie, and 5 State of New York, have invented certain new and useful Improvements in Broom-Head Holders, of which the following is a specification.

This invention relates to broom head 10 holders.

My object is to provide a detachable broom head and handle, whereby when one broom head is worn out or for any reason no longer of use, it may be detached from 15 its handle and thrown away and another broom head substituted therefor, thus saving the cost of a broom handle whenever a new broom is desired.

Another object is to provide a broom head 20 constructed in a new manner and a detachable handle of novel construction adapted to coöperate therewith.

One object is the provision of a broom handle having a novel attachable broom 25 holder which will permit a broom head to be readily inserted thereinto or removed therefrom in a quick and convenient manner.

A further object is the provision of a broom having a detachable head and a 30 holder therefor which may be constructed at comparatively low cost and whereby the broom head will be securely held ready for convenient attachment at any time.

The invention resides in certain novel 35 constructions, arrangements and adaptations of parts more fully set forth herein- after and recited in the appended claims, certain embodiments of the invention being shown in the accompanying drawings in 40 which—

Figure 1 is a side view showing the broom head in position and the holder closed; Fig. 2, a view looking toward the opposite side of Fig. 1; Fig. 3, an edge view partly in section, showing the broom head in position; Fig. 4, a detail view of the broom head; Fig. 5, a detail perspective of the clamping handle and links; Fig. 6, a similar view of a modification thereof.

50 The broom head 1 is provided with the usual stitching 2 to hold the bristles thereof together. In respect of the broom head, my invention consists in dipping or impregnating the upper end 3 in some suitable adhesive material to aid in securing the bristles together and; also, in cutting away the

head at 4 to provide shoulders 5, whereby the broom head is held against lateral displacement in any form of the holder herein- after described. I also find it advisable to 60 secure the bristles together in addition to the usual stitching by wire stitching 6.

A broom head constructed as set forth has considerable rigidity at its upper end enabling it to be readily clamped and securely 65 held by the holder set forth hereinafter. This head is set forth and claimed in another application, filed Aug. 5, 1912, Serial No. 713,386, broom.

To any suitable handle 7 is secured in 70 any suitable manner at 8, the clamping jaws 9 and 10 of the holder, these being flexible and provided with teeth 11 and rounded edges 12, whereby lateral displacement of the broom head is prevented and no projec- 75 tions are afforded which would catch on the clothing or objects or would injure furniture. These sections 9 and 10 may be stampings, but they may be otherwise formed. In the section 9 there are a lon- 80 gitudinal depression 13 and a transverse de- pression 14, the two intersecting. There are also provided openings 15. In the section 10 are depressions 16 and openings 17.

The clamping handle 18 is adapted to lie 85 in the longitudinal depression 13 when the sections 9 and 10 clamp the broom head and the fulcrum 19 lies in the depression and is provided with cranks 20 to which are connected links 21 that extend through the open- 90 ings 15 and 17, there being provided mem- bers 22 connected to said links which lie in depressions 16. Disposed between the sec- tions of jaws 9 and 10 is a spring 23 which may be a leaf spring and provided with a bi- 95 furcated end 24 straddling the raised part below the depression 13 and the other end of the spring bearing against the raised parts formed by the depressions 16, whereby the spring is anchored without requiring any attaching means therefor. The spring 100 23 opens the jaws when the handle 18 is moved to permit said spring to act, the jaws then being in position to permit the intro- duction of the broom head between them. 105

As shown in Fig. 6, the handle 18^a and its fulcrum 19^a and the cranks may be formed of a single piece of wire and the links 21^a and their members 22^a may be formed of single pieces of wire.

110 The broom head having been inserted be- tween the jaws or sections 9 and 10 and the

latter being clamped together, the teeth firmly engage and hold the broom head and the rounded edges of the holder, as also the shoulders 5 on the broom head and prevent lateral play of the latter. The broom may be used until it is worn out and then detached from the holder and thrown away and another substituted.

Having thus described my invention, what I claim as new and desire to secure by Letters Patent, is:—

1. A broom holder consisting of spaced sheet metal clamping jaws movable toward and away from each other, arranged and adapted at one end to receive and hold a broom head therebetween and at their other end having a socket adapted to receive a handle, a spring coöperating with said jaws, a crank shaft on one of said jaws, links connecting the cranks of said shaft with the other jaw, the said jaws being provided with openings through which the links extend and a lever for operating said crank shaft, said lever and links being permanently and relatively stationarily carried by the clamping jaws inwardly from the broom receiving end of the latter, whereby a broom head may be inserted between or removed from said jaws without removing said lever and links.
2. A broom holder having spaced clamping jaws, one of which is provided with a transverse depression, a crank shaft located

in said depression which constitutes a bearing and retaining means therefor, links connecting the cranks of said crank shaft with the other clamping jaw, the said jaws being provided with openings through which the links extend and a lever for said crank shaft which is adapted, when operated, to draw the clamping jaws together.

3. A broom holder having sheet metal clamping jaws, each provided with transversely arranged depressions and one of them having another depression disposed at an angle to the depression aforesaid, a combined crank shaft and handle made from a single piece of wire, the crank shaft of which lies in one of the transverse depressions which constitutes a bearing and retaining means therefor, the handle being adapted to be positioned in the angularly arranged depression aforesaid, links engaged with the cranks of the crank shaft and extending through the clamping jaws, and means engaging the links, said means lying in the transverse depression in the other clamping jaw.

In testimony whereof, I hereunto affix my signature in presence of two witnesses.

WILLIAM M. CHRISTOPHER.
